C. C. TOMKINSON

CONCRETE INSERT

Filed Jan. 27, 1921

Inventor

Charles C. Tomkinson

By his Attorney

E. W. Marshall

UNITED STATES PATENT OFFICE.

CHARLES C. TOMKINSON, OF PLAINFIELD, NEW JERSEY, ASSIGNOR TO J. EDWARD OGDEN, OF MOUNTAINVILLE, NEW YORK.

CONCRETE INSERT.

Application filed January 27, 1921. Serial No. 440,355.

To all whom it may concern:

Be it known that I, CHARLES C. TOMKINSON, a citizen of the United States, and a resident of Plainfield, county of Union, and State of New Jersey, have invented certain new and useful Improvements in Concrete Inserts, of which the following is a specification.

This invention relates to concrete inserts adapted to form supports for anchoring means such as nuts or headed bolts and it is an object of the invention to form the inserts of sheet metal in such manner that they may be cheaply manufactured and easily assembled.

With the foregoing and other objects in view, the invention consists in the novel construction, combination and arrangement of parts to be hereinafter specifically described in connection with the accompanying drawings forming part of this specification, reference being had, however, to the appended claims for the scope of the invention.

Referring now to the drawings, Fig. 1 is a perspective view of one embodiment of my invention showing a nut within the insert, and

Fig. 2 is a side elevation thereof showing the nut within the insert as operatively connected to the end of a bolt or round bar.

Fig. 3 is a view similar to Fig. 1 but showing the insert as long enough to provide for the entry and slidable adjustment of an anchor element.

Fig. 4 is a perspective view of a modified form of the invention.

Fig. 5 is a side elevation of the same and

Fig. 6 is a longitudinal sectional elevation of the anchor shown in Fig. 3.

Like characters of reference designate like parts throughout the several views.

The insert is made up of two members 10 and 11. The member 10 is U-shaped and has a restricted portion 12 whereby ledges 13 are formed. These ledges 13 form abutments for preventing displacement in one direction of the anchor element shown in Fig. 1, as a nut N, and also serve as means for retaining the compartment-forming member 11 in combinative association with the other member 10. The member 11 preferably takes the form of a U-shaped element of a height sufficient to form a pocket into

which the end of a bolt B cooperating with the nut N may project.

The member 11 at its terminals has wings 14 which engage under the ledges 13 thus preventing separation of the members 10 and 11 in one direction. For securing the said members against movement in another direction, flanges 15 extending from the terminals of the member 11 are provided. These flanges overlap the adjacent edges of the member 10 and are then bent outwardly at right angles to form nailing tabs 16 having notches 17 for the reception of nails or other means for securing the insert to a mold or other fixed support while the concrete is being poured.

The member 10 has its terminals flared outwardly to form wings 18 terminating in out-turned flanges 18'. These when embodied in concrete offer great resistance to the withdrawal of the insert.

As shown in Fig. 3, the insert may be of sufficient length to allow for the slidable adjustment of the anchors. In order to provide for the entry or removal of a bolt head or other headed anchor, the slot is widened to form a gateway. The distance between the ends 19 of the flanges of the slot S and the opposite end 19' of the insert is preferably less than the depth or thickness of the anchor so as to require tilting of the same in order to permit its passage through the gateway. This arrangement insures that the anchor will not be displaced from its compartment so long as it is in normal position even though it is at the extreme end of the slot since part of the anchor will overlie the edge 19. When the anchor is a bolt the shank thereof must be tilted so as to overlie the slot S to permit the entry of the head through the gateway, the head being rocked and slid on the end edges 19.

The insert in Fig. 3 is shown as having the compartment-forming U member 11^a as of less height than in the previously described form. This is for the reason that no provision need be made for a through-the-nut-projecting end of the shank of the bolt. The member is wide enough so that its top edges will abut the ledges 13 instead of merely having a hooked engagement therewith as in Fig. 1, and is, in effect, an inverted drawer held from upward displacement by the ledges 13.

As shown in Fig. 4 the ledges 13 may be formed in the compartment-forming member 11' corresponding to member 11. In this construction, however, the ledges do not co-
5 operate with the other U member 10' to hold it in relatively fixed position as in the preferred form but instead thereof securement is effected by providing tongues 20 at the terminals of the member 11' and bending the
10 same over onto the bottom of the U member 10' through notches 21 in the side edges of said member. These edges are notched sufficiently deep to permit nails or securing means to be used in securing the insert to
15 a mold or other fixed support while the concrete is being poured.

While I have described the invention in great detail, I desire it to be understood that I intend no limitations other than such
20 as may be imposed by the appended claims.

What I claim is:

1. In a concrete insert, the combination of a substantially U-shaped member having in-

wardly projecting ledges extending lengthwise of the same to form longitudinally extensive shoulders and a second U-shaped member oppositely disposed within the first to form a compartment and having its ends engaged beneath the shoulders provided by the ledges so as to maintain the ends of the compartment securely closed. 25

2. In a concrete insert, the combination of a U-shaped member having the sides of the same constricted to provide a pair of inwardly projecting ledges and a second U-shaped member oppositely disposed within the first to form a compartment and having its ends engaged beneath the ledges formed by the constricted portions of the sides, whereby said ends of the second member are 35 confined in their compartment-forming relation with the first member. 40

In witness whereof, I have hereunto set my hand this 17th day of January, 1921.

CHARLES C. TOMKINSON.
